UNITED STATES PATENT OFFICE.

JOHN HOPE, JR., OF PROVIDENCE, RHODE ISLAND.

LATCH.

SPECIFICATION forming part of Letters Patent No. 431,845, dated July 8, 1890.

Application filed December 3, 1889. Serial No. 332,367. (No model.)

To all whom it may concern:

Be it known that I, JOHN HOPE, Jr., of the city of Providence, in the county of Providence and State of Rhode Island, have invented a new and useful Improvement in Door-Latches; and I hereby declare that the following is a full, clear, and exact description of the same, reference being had to the accompanying drawings, forming part of this specification.

This invention has reference to an improvement in latches for doors, operated by the knobs on each side of the door and provided with a device by means of which the latch is locked.

The invention consists in the peculiar and novel construction of the latch, its connection with the door-knobs, and the device by which the bolt is connected with or disconnected from the latch-frame, as will be more fully set forth hereinafter.

Figure 1 is a side view of the latch and part of the door and door-jamb, showing the latch-frame and operating-pins in broken lines. Fig. 2 is a sectional view of the latch, showing the same secured to a door. Fig. 3 is a sectional view of part of the latch, showing the bolt separated from the latch-frame in the locked position. Fig. 4 is a sectional view of the latch on the line A B. Fig. 5 is another sectional view of the latch on the line C D.

Similar numbers of reference indicate corresponding parts throughout.

In the drawings, the number 6 indicates a metal frame extending across the edge of the door and along the sides, and secured to the door by entering the part extending across the edge into the door, so that the outer surface is flush with the edge of the door, and then passing the bolt 7 through the door and screwing the end into the opposite end of the frame 6, as is shown in Fig. 2.

The metal frame 6 is provided on its inner sides with the recess 8, in which the latch-frame 9 slides. The bosses 10 are formed one on each of the sides of the metal frame 6, and in the bosses 10 are supported the pintles 11, having the disks 12, from which the pins 13 project, each one of the disks being secured to one end of the pintle and the knob 14 to the other end. The latch-frame 9

is provided with the opening 15, into which the pin 13 enters. As the pin 13 is secured away from the center of the pintle 11, by turning either one of the knobs 14 the latch-frame 9 is made to slide in the recess 8, so as to reciprocate therein. The end of the latch-frame 9 extending across the thickness of the door is provided with the cylindrical projection 16, around which the coiled spring 17 is placed. The said spring 17, entering a hole bored into the door, bears on the latch-frame and the door and holds the latch in the closed position when the knobs are released. The latch-frame 9 is provided at its forward end with the locking-heads 18, and similar locking-heads or buttons 19 are secured to and project from the inner face of the part of the frame 6 extending across the door.

The plate 20, to which the bolt 21 is secured, has the locking-lever 22 pivotally secured to its inner side. One end of the locking-lever 22 extends through the L-shaped opening 23. When the projecting end of the lever is raised, the lever 22 connects the plate 20 and bolt 21 with the locking-heads or buttons 19, and thus secures the bolt to the metal frame 6 and separates the same from the latch-frame 9. By turning one or both of the knobs 14 the latch-frame is reciprocated, but the locking-bolt is firmly held in the locked position, so that the door cannot be opened. When now the lever 22 is depressed, it will be disengaged from the locking-heads 19 and pass under the locking-heads 18, secured to the latch-frame 9, and connect the bolt 21 with the latch-frame, so that when either one of the knobs 14 is turned the latch-frame 9, the plate 20, bolt 21, and lever 22 will reciprocate together, the lever 22 sliding in the horizontal part of the L-shaped opening 23. By this construction a simple and durable spring-latch is secured which can be operated by either of the knobs, to be used as a simple latch, and can be locked on one side of the door by raising the end of the lever 22 into the vertical arm of the L-shaped opening in the frame 6.

Having thus described my invention, I claim as new, and desire to secure by Letters Patent—

1. A door-latch consisting of a metal frame

extending across the edge and along both sides of the door, provided with knobs having eccentric crank-pins, a latch-frame operated by the knobs, and a bolt provided with a lever, 5 constructed to engage with locking-studs to connect the bolt with the outer frame or the latch-frame, as and for the purpose herein set forth.

2. The combination, in a spring-latch, with 10 the frame 6 and the knobs 14, provided with the eccentric pins 13, of the latch-frame 9, the spring 17, the locking-heads 18 and 19, the bolt 21, plate 20, and locking-lever 22, as described.

3. The combination, in a locking-latch, with 15 the frame 6, bosses 10 10, pintles 11, disks 12, pins 13, the L-shaped opening 23, the recess 8, and bolt 7, of the latch-frame 9, provided with the locking-heads 18, the plate 20, provided with the bolt 21 and the lever 22, and the locking-heads 19, extending from the inner face of the frame 9, constructed to be reciprocated by the knobs 14 or secured in the locked position, as described.

JOHN HOPE, JR.
